UNITED STATES PATENT OFFICE.

CARL MAGNUS SANDBERG AND CHRISTIAN DONATUS ROMANUS SANDBERG,
OF McPHERSON, KANSAS.

CULTIVATOR.

SPECIFICATION forming part of Letters Patent No. 393,667, dated November 27, 1888.

Application filed August 16, 1888. Serial No. 222,851. (No model.)

To all whom it may concern:

Be it known that we, CARL MAGNUS SANDBERG and CHRISTIAN DONATUS ROMANUS SANDBERG, citizens of the United States, residing at McPherson, in the county of McPherson and State of Kansas, have invented new and useful Improvements in Cultivators, of which the following is a specification.

Our invention relates to improvements in cultivators; and it consists in certain novel features hereinafter described and claimed.

In the accompanying drawings, which fully illustrate our invention, Figure 1 is a perspective view of our improved cultivator. Fig. 2 is a rear view of the same, and Fig. 3 is a detail view of an extension for the shovel.

Referring to the drawings by letter, A designates the ordinary cranked axle having the usual supporting-wheels, B B.

C designates the forwardly - converging beams having their rear ends connected by a cross-bar, D, as shown. The rear ends of the forwardly-converging bars or main beams C are provided with the hooks E, over which the cultivator-beams F are engaged when the machine is not in use. The cultivator-beams F are secured to the axle by the couplings G, and at their rear ends they are provided with the integral standards H, as shown.

It will be observed that the beams are arranged in pairs, the beams of each pair diverging rearwardly and the inner beam of each pair being somewhat longer than the outer beam. This arrangement brings the inner standard to the rear of the outer standard and causes the shovels or scrapers I, secured thereto, to converge rearwardly and inwardly, as shown. These shovels or scrapers are convex in cross-section, extend entirely across the

space between the lower ends of the standards, and have their opposite ends connected to the standards by means of the lugs J, which project from the rear sides of the scrapers and are bolted to the lower ends of the standards, as shown. The handles J' are secured to the cultivator beams in the usual or any preferred manner and project upward and rearward therefrom. In the cross-bar D, connecting the rear ends of the main beams, we form a central

vertical opening, in which is mounted a vertical rod, K, having a head or flange, L, at its

upper end and provided with an eye or hook, M, at its lower end. A coiled spring, N, is arranged around the upper portion of the rod K, between the head or flange L and the cross-bar D, and serves to keep said rod normally elevated. The lower end of the rod is connected to the cultivator-beams by the flexible chains O, which have their upper ends connected to the lower end of the rod and their lower ends secured to the beams. This arrangement of the rod, spring, and chains serves to keep the shovels or scrapers normally elevated, as before stated, so that they will take into the earth but a short distance. When it is desired to cut into the soil to a greater depth, the handles are depressed, so as to lower the shovels, the spring yielding sufficiently, as will be readily understood, but at the same time exerting an upward pressure thereon to cause the shovels to cut uniformly to the same depth. This arrangement of devices also permits the shovels to be spread apart, so as to pass by obstructions, but draws them quickly together again into proper working positions after the obstruction has been passed.

In practice, the cultivator is drawn along the field in the usual manner, the shovels or scrapers passing on opposite sides of the row of corn. The scrapers will then take up the loose dirt between the rows of corn and throw the same around the roots of the plants, leaving the spaces between the rows smooth and even. The shovels being concave on their front faces the dirt cannot pass rearward over the upper edge of the same, so that the work done by our cultivator is very clean and effective.

In the event that the shovels or scrapers are not long enough to throw the dirt well up around the plants, the supplemental plates z z (shown in Fig. 3) may be secured thereto. These plates are similar in shape and construction to the scrapers and are bolted or otherwise secured thereto at the inner ends thereof.

Our cultivator is very simple and efficient, and its advantages are thought to be obvious.

Having thus described our invention, what we claim, and desire to secure by Letters Patent, is—

1. The combination of the cultivator-frame comprising the axle and the beams mounted

thereon and having their rear ends connected by a cross-bar, D, the rod K, mounted vertically in a central opening in said cross-bar and having a flange, I, at its upper end and the eye M at its lower end, the spring coiled around the rod K between the flange I and the cross-bar D, the cultivator-beams secured to the axle, and the diverging chains having their upper ends secured to the eye M and their lower ends secured to the cultivator-beams, as set forth.

2. The combination of the cultivator-beams arranged in pairs, the members of each pair diverging and having integral standards at

their rear ends, the scrapers secured to the lower ends of said standards and made convex in vertical section, and the supplemental convex plates secured to the inner ends of said scraper, as specified.

In testimony that we claim the foregoing as our own we have hereto affixed our signatures in presence of two witnesses.
